UNITED STATES PATENT OFFICE.

ELIHU THOMSON, OF SWAMPSCOTT, MASSACHUSETTS, ASSIGNOR TO GENERAL ELECTRIC COMPANY, A CORPORATION OF NEW YORK.

TELEPHONE METERING SYSTEM.

1,121,953.

Specification of Letters Patent. Patented Dec. 22, 1914.

Application filed February 15, 1912. Serial No. 677,824.

To all whom it may concern:

Be it known that I, ELIHU THOMSON, a citizen of the United States, residing at Swampscott, county of Essex, State of Massachusetts, have invented certain new and useful Improvements in Telephone Metering Systems, of which the following is a specification.

My invention relates to telephone meters, and particularly to that type of meter which records the length of time a calling subscriber's instrument is in use.

The objects of my invention are generally to provide improvements in the method of operating a telephone circuit so as to actuate a meter located at a subscriber's instrument by means of apparatus located at the central exchange.

More specifically, my invention aims at the provision of a method for periodically varying or reversing the direction of flow of the current in a telephone circuit, in which such changes of current condition actuate the counting train of a meter at the subscriber's end of the line.

A further object of my invention is to provide an apparatus for the exchange equipment which will successfully carry out my improved method of operation, and which, in connection with a suitable metering apparatus at the subscriber's end of the line, will satisfactorily register the time the telephone apparatus is in use without interfering with the operation of the same.

Several methods have already been proposed for indicating by a meter the length of time a telephone is in use, but so far as I am aware they have all been open to objection because of the interference which has resulted with the telephone service. This interference has generally consisted in objectionable noises in the receiving instrument of such an undesirable character as to render the meter apparatus entirely impracticable. My invention eliminates these objectionable features of telephone metering, and provides a method of and means for obtaining an accurate registration of the length of time the telephone is in use without in any manner interfering with the usual operation of the instrument.

Although my invention is adapted to be used in connection with any type of telephone meter which depends for its actuation upon a change in the current condition

of the telephone circuit it is particularly adapted to be used in connection with that type of telephone meter in which the current supplied to the calling subscriber's line is reversed at short and regular intervals. These reversals of current operate the meter recording mechanism and thus serve to indicate the length of time the instrument is in use. My invention as applied to this type of meter consists in employing a counter electromotive force, as for example, dynamo induction, to oppose the usual battery located at the exchange at periodic intervals of time and simultaneously to impress on the telephone circuit an electromotive force, equal and opposite to that of the battery. It will thus be seen that this counter electromotive force must be twice as large as the electromotive force of the battery, so that the resulting electromotive force causing a flow of current in the reverse direction to that caused by the battery, is approximately the same as the battery electromotive force. I have found that a generator whose field circuit is periodically opened and closed, furnishes the best source of supply for the counter electromotive force. By properly designing the field of this generator, the length of time required for building up the field and the length of time required for the decay of the same may be made approximately equal. Under such circumstances, the voltage at the generator terminals will rise very quickly, and at the same time very smoothly, and will thus occasion little or no disturbance in the telephone circuit.

For a better understanding of my invention, reference is to be had to the accompanying drawing, in which the figure shows diagrammatically the novel features of my invention as incorporated in a usual telephone circuit.

In the drawing, where I have shown my invention in connection with that type of meter which depends for its operation upon a reversal of current in the telephone circuit, A and B represent the usual telephone instruments of two subscribers. The central exchange outfit is indicated at C. Near each subscriber's instrument is placed a meter which consists broadly of a permanent magnet 5, having the peculiar shaped pole pieces 6 and 7 and pivoted armature 9, adapted to be rocked by reversals of the current in the coil 8, which latter is secured to

the armature and is in series with the telephone circuit. The rocking of the armature actuates through its pawl 10 the first gear 11 of the counting train of the meter. Since 5 the reversals of current occur at regular and frequent intervals, the counting train gives by its registration the length of time the instrument is in use. The central exchange equipment comprises the usual storage battery 12, the supervisory relays indicated diagrammatically at 13, and the condensers 13^a. These features form no part of my invention, and are of the customary construction.

15 In the circuit of one of the supervisory relays, I include the novel features of my invention. The generator 14 has its armature terminals connected across a non-inductive resistance 15 in series with an inductance 16 of very low resistance. The resistance 15 is included in the circuit of the supervisory relay. The generator field is excited from any source of current, as for example, the direct current mains 17. A 20 clock 18 operates at regular intervals to close the contacts 19 of a relay and this energizes the switch closing mechanism 20. The circuit through the generator field is thus completed and broken at regular intervals and the terminal voltage of the generator is correspondingly varied from full voltage to zero.

The voltage of the generator 14 should be, as nearly as possible, twice that of the battery 12. In practice this condition can only be approximated, and it is to be understood that such approximation is entirely satisfactory for the operation of my invention. When the generator 14 is operated, and generates 35 approximately twice the voltage of the battery 12, its electromotive force will oppose that of the battery and at the same time reverse the direction of the flow of current in one side of the circuit, namely, the 40 side in which the generator is located. When the generator field circuit is broken and the battery is supplying current to the telephone circuit, the direction of flow of the current in the circuit will be as indicated 45 by the full line arrows in the drawings, and when the field circuit is closed by means of the clock and its co-operating mechanism, and the generator is supplying current to the circuit, the direction of flow of the current will be as shown by the dotted line arrows. When the generator is thus 50 operating under the best conditions no current flows through the battery.

The generator, for the best results, should 55 have a smooth core armature with a commutator having a large number of segments and few armature turns per coil. There should also be two brushes per pole and each brush should span several commutator segments. The smooth core is desirable in

order to minimize the humming in the telephone circuit, which would be present if a toothed core armature were used. Few turns per coil are employed in order that the change in the inductance of the circuit, 70 due to the armature coils passing beneath the brush, may be as small as possible. The brushes should span several commutator segments in order that the current in the short circuited armature coil beneath the 75 brush may be brought well within the influence of the incoming field before being cut into the circuit. Two brushes per pole are advisable in order to insure a more uniform contact resistance.

80 The field turns of the generator should be few in order that the time constant may be as small as possible. The decay of the field flux in standard machines is much more rapid than the building up. This is due to 85 the inductance of the field, the electromotive force of which opposes the rapid rise of the current when the field switch is closed. The time in which a given field will build up depends upon the ratio of the inductance 90 to the resistance, while the rate of decay depends upon the design of the machine. Therefore, the most satisfactory result will be obtained with a given design, when the time of building up is equal to the time of 95 decay of the field.

The operation of my device is as follows: When subscriber B takes his receiver from the hook and thus calls the central operator, the latter will place the answering cord 21, 100 comprising the usual tip and sleeve, in the proper switchboard jack and will then insert the calling cord 22 in the jack of the second subscriber, A, who is being called. The apparatus being thus connected, the 105 clock periodically, for example, every fifteen seconds, operates the time switch 20, and the generator field is thus regularly and periodically energized. The gradual building up and subsequent decay of the generator field produces a corresponding gradual change in the voltage of the generator and thus a reversal of the current is effected without in any way interfering with the 110 telephone circuit. It is desirable to insert 115 the generator in the circuit as quickly and as smoothly as possible, in order that the zero of current may be crossed at such a rate as not to interfere with speech. Under such 120 circumstances, there is no interference with the operation of the telephone circuit. The building up and decay of the generator field has been found a most admirable and satisfactory method of inserting a counter electromotive force in the circuit. The rise in 125 voltage upon the building up of the field is very smooth and rapid, and the fall in voltage upon the decay of the field is similarly smooth and rapid. The time required for the building up of the field should be the 130

same as that consumed in the decay, and as previously stated, the generator is so designed that this result is accomplished.

It will be readily understood by an inspection of the drawing that only the current in the line of subscriber B is reversed and hence only the meter at B's instrument records the length of time the telephone is used.

10 The resistance 15 and inductance 16 are not necessary for the satisfactory operation of my invention. It has been found in practice, however, that the use of these additional elements reduces to zero all humming and objectionable noises in the telephone instruments due to the commutation of the generator coils.

I do not desire to be limited in the application of my invention to telephone meters which rely specifically on a reversal of current for their operation, since my invention is adapted to be used in connection with any telephone meter which relies for its operation upon a change in the current condition of the telephone circuit. It is evident that the meter at the subscriber's end of the line may be operated by varying the current in the telephone circuit instead of by reversing the current, and my invention is adapted to be used in either case.

What I claim as new and desire to secure by Letters Patent of the United States is:—

1. The method of actuating a meter adapted to be operated by a change in the current condition of a telephone circuit which consists in periodically changing the supply of the telephone operating current of said circuit from one source of electromotive force to a separate source of electromotive force, and normally employing the current supplied from each source of electromotive force for the normal operation of a telephone instrument in said circuit.

45 2. The method of actuating a meter adapted to be operated by a change in the current employed for the normal operation of a telephone instrument in said circuit which consists in periodically changing the supply of current to said circuit for the operation of said instrument from one source of electromotive force to a separate source of electromotive force, so that the flow of the telephone operating current is altered by each periodic change of the source of supply of electromotive force.

3. The method of actuating a meter adapted to be operated by varying the current in a telephone circuit which consists in maintaining a source of potential connected to said circuit and periodically opposing said source of potential by a second source of potential.

45 4. The method of actuating a meter adapted to be operated by varying the current in a

telephone circuit which consists in maintaining a source of potential connected to said circuit, periodically opposing said source of potential by a second source of potential and simultaneously supplying current to said circuit from said second source of potential.

5. The method of actuating a meter adapted to be operated by varying the current in a telephone circuit, which consists in maintaining a battery and an electric generator connected to said circuit, periodically energizing the field of said generator and employing the resulting electromotive force to oppose the electromotive force of said battery and to supply current to said circuit.

75 6. The method of actuating a meter adapted to be operated by reversing the current in a telephone circuit that employs a battery as a source of current, which consists in opposing the battery by dynamo induction and simultaneously supplying a reversed current to the circuit.

80 7. The method of actuating a meter adapted to be operated by reversing the direction of flow of current in a telephone circuit, which consists in opposing the electromotive force of the primary source of current by a generator and simultaneously supplying current to said circuit from said generator in a direction reversed to that due to the primary source.

85 8. The method of actuating a meter adapted to be operated by periodically reversing the direction of flow of current in a telephone circuit, which consists in maintaining a source of potential connected to said circuit, periodically opposing said source of potential by a second source of potential and simultaneously impressing on said circuit a potential equal and opposite to said first source.

90 9. The method of actuating a meter adapted to be operated by periodically reversing the direction of flow of current in a telephone circuit, which consists in maintaining a storage battery and a generator connected to said circuit, periodically energizing the field of said generator and utilizing the resulting electromotive force to oppose the electromotive force of the battery and to supply the circuit with current in the reversed direction to that supplied by the battery.

10. The method of actuating a meter adapted to be operated by periodically reversing the direction of flow of current in a telephone circuit, which consists in maintaining a source of potential connected to said circuit, periodically generating a second source of potential and employing said second source of potential to oppose said first source and also to supply current to said circuit in a reversed direction to that supplied by said first source.

11. The method of actuating a meter adapted to be operated by periodically reversing the direction of flow of current in a telephone circuit, which consists in maintaining a storage battery and a generator whose full voltage is approximately twice that of the battery connected to said circuit, periodically energizing the field of said generator and employing the resulting electromotive force of the generator to oppose the electromotive force of the battery and simultaneously supplying current to the circuit from the generator in a reversed direction to that supplied by the battery.
12. In a telephone circuit, a meter adapted to be operated by a change in the current condition of the telephone circuit, a source of current connected to said circuit, and means for periodically opposing during the period that a telephone instrument in said circuit is in use the electromotive force of said source of current.
13. In a telephone circuit, a meter adapted to be operated by a change in the current condition of the telephone circuit, a source of current connected to said circuit, and means for periodically opposing the electromotive force of said source of current and for simultaneously supplying current to said circuit.
14. In a telephone circuit, a meter adapted to be operated by a change in the current condition of the telephone circuit, a source of current connected to said circuit, and means for periodically opposing the electromotive force of said source of current and for simultaneously supplying current to said circuit in a reversed direction to that supplied by said source.
15. In a telephone circuit, a meter adapted to be operated by a change in the current condition of the telephone circuit, a battery connected to said circuit, and means for periodically opposing during the period that a telephone instrument in said circuit is in use the electromotive force of said battery by dynamo induction.
16. In a telephone circuit, a meter adapted to be operated by a change in the current condition of the telephone circuit, a battery and a generator connected to said circuit, and means for periodically opposing during the period that a telephone instrument in said circuit is in use the electromotive force of the battery by the electromotive force of the generator.
17. In a telephone circuit, a meter adapted to be operated by a change in the current condition of the telephone circuit, a battery connected to said circuit, and means for periodically opposing the electromotive force of the battery and for simultaneously supplying current to said circuit.
18. In a telephone circuit, a meter adapted to be operated by a change in the current condition of the telephone circuit, two independent sources of electromotive force for supplying current to said circuit, and means for periodically opposing the electromotive force of one of said sources by the electromotive force of the other of said sources and for supplying current to said circuit from said last mentioned source.
19. In a telephone circuit, a meter adapted to be operated by a change in the current condition of the telephone circuit, a source of current connected to said circuit, an electric generator connected to said circuit, and means for periodically opposing during the period that a telephone instrument in said circuit is in use the electromotive force of said source by the electromotive force of said generator.
20. In a telephone circuit, a meter adapted to be operated by a change in the current condition of the telephone circuit, a source of current connected to said circuit, an electric generator, means for periodically energizing during the period that a telephone instrument in said circuit is in use the field of said generator, and electrical connections for opposing the electromotive force of said source by the resulting electromotive force of said generator.
21. In a telephone circuit, a meter adapted to be operated by a change in the current condition of the telephone circuit, a source of current connected to said circuit, an electric generator, means for periodically energizing the field of said generator, and electrical connections for opposing the electromotive force of said source by the resulting electromotive force of the generator and for simultaneously supplying current to said circuit from said generator.
22. In a telephone circuit, a meter adapted to be operated by a change in the current condition of the telephone circuit, a battery connected to said circuit, and means for smoothly and rapidly opposing the electromotive force of said battery and for supplying a reversed current to said circuit.
23. In a telephone circuit, a meter adapted to be operated by a change in the current condition of the telephone circuit, a battery connected to said circuit, an electric generator connected to said circuit so as to oppose said battery and means for periodically employing the electromotive force of said generator to oppose the electromotive force of said battery and for simultaneously supplying current to said circuit by said generator.
24. In a telephone circuit, a meter adapted to be operated by a change in the current condition of the telephone circuit, a battery connected to said circuit, an electric generator having its armature terminals connected to a non-inductive resistance in series with an inductance, connections between the

- non-inductive resistance and the circuit so that the voltage across said resistance opposes the electromotive force of the battery when the generator field is energized, and 5 means for periodically energizing the field of said generator.
25. In a telephone circuit, a meter adapted to be operated by a change in the current condition of the telephone circuit, a battery 10 connected to said circuit, an electric generator whose normal electromotive force is approximately twice that of the battery, and means for periodically opposing the electromotive force of the battery by the 15 electromotive force of the generator and simultaneously supplying current to the circuit from said generator.
26. In a telephone circuit, a meter adapted to be operated by a change in the current
- condition of the telephone circuit, a battery 20 connected to said circuit, an electric generator having its armature terminals connected across a non-inductive resistance in series with an inductance, connections between said battery and said resistance, and 25 means for periodically impressing on said resistance during the period that a telephone instrument in said circuit is in use an electromotive force approximately twice as great as the electromotive force of the 30 battery and opposite in direction.

In witness whereof, I have hereunto set my hand this 13th day of February 1912.

ELIHU THOMSON.
